FREEZER CABINET OR SIMILAR ARTICLE

Robert D. Budlong, Skokie, Ill., assignor to Amana
Refrigeration, Inc., Amana, Iowa, a corpora-
tion of Iowa

Application February 3, 1954, Serial No. 28,817

Term of patent 14 years

(Cl. D67—3)

To all whom it may concern:

Be it known that I, Robert D. Budlong, a citizen of the United States, residing at Skokie, in the county of Cook and State of Illinois, have invented a new, original, and ornamental Design for a Freezer Cabinet or Similar Article, of which the following is a specification, reference being had to the accompanying drawing, forming a part thereof.

In the drawing:

Figure 1 is a perspective view of a freezer cabinet or similar article showing my new design;

Figure 2 is a top plan view thereof on a reduced scale;

Figure 3 is a side elevational view thereof also on a reduced scale.

The opposite side to that shown in Figure 3 is plain.

The dominant features in my design reside in the portions shown in full lines.

I claim:

The ornamental design for a freezer cabinet or similar article, substantially as shown and described.
